(57) **CLAIM**

The ornamental design for a circle cutting jig, as shown and described.

DESCRIPTION

FIG. 1 is a perspective view of the circle cutting jig showing our new design.

FIG. 2 is a top view of the circle cutting jig showing our new design.

FIG. 3 is a bottom view of the circle cutting jig showing our new design.

FIG. 4 is an end view of the circle cutting jig showing our new design.

FIG. 5 is an opposite end view of the circle cutting jig showing our new design.

FIG. 6 is a side view of the circle cutting jig showing our new design; and,

FIG. 7 is an opposite side view of the circle cutting jig showing our new design.

The broken lines in the drawings depict the boundaries of the claimed design and form no part thereof.
